UNITED STATES PATENT OFFICE.

FRANK E. HULETT, OF CLEVELAND, OHIO.

CLAM-SHELL BUCKET AND OPERATING MECHANISM.

SPECIFICATION forming part of Letters Patent No. 696,444, dated April 1, 1902.

Application filed March 23, 1901. Serial No. 52,535. (No model.)

To all whom it may concern:

Be it known that I, FRANK E. HULETT, a resident of Cleveland, in the county of Cuyahoga and State of Ohio, have invented certain new and useful Improvements in a Combined Clam-Shell Bucket and Operating Mechanism Therefor; and I do hereby declare the following to be a full, clear, and exact description of the invention, such as will enable others skilled in the art to which it pertains to make and use the same.

This invention relates to new and useful improvements in a combined clam-shell bucket and operating mechanism therefor especially adapted for handling iron ore and similar material.

The object of my invention is to provide a combined bucket and operating mechanism therefor which will be powerful, easily handled, and capable of being operated without unprofitable expenditure of energy.

My invention therefore consists in providing new and improved means for suspending and transmitting power to the scoops constituting the respective halves of the bucket, whereby the excavating power of the bucket is greatly increased and the scoops while excavating will constantly be in an advantageous position for entering the material to be excavated, thus necessitating an expenditure of energy but slightly in excess of what is actually needed to drive the scoops through the material being excavated.

My invention further consists in the features of construction and combinations of parts hereinafter described in the specification, illustrated in the drawings, and pointed out in the claims.

The class of devices to which my invention particularly relates is designed for handling coal, ore, and other heavy material, and as in common use at present the bucket proper generally comprises two scoops adapted to form a single receptacle when their cutting edges are brought into contact. These scoops are so suspended from the framework carrying the operating mechanism that when the front or cutting edges of the scoops enter the material to be excavated the bottoms of the scoops are often elevated at such an angle that the excavated material is prevented from passing up into the respective scoops and is

actually compressed between the forward ends of the opposing bottoms of the respective scoops as they approach each other. In order to close the bucket, sufficient power must be exerted to force the material in the front ends of the scoops up the inclined bottoms. The closing operation thus involves a compressing and shifting of a portion of the load taken into the bucket, causing a wasteful expenditure of energy and frequently resulting in injury to the operating mechanism. Therefore with the buckets now in common use the operating mechanism must not only be powerful enough to force the scoops through the material being excavated, but must also have sufficient strength to compress or displace a portion of the load in the front part of the scoops and force it up into the rear parts thereof. By my invention I suspend the respective scoops and connect them with the operating mechanism in such a manner that the rear portion of each scoop is caused to travel more rapidly than the front portion when the bucket is being operated—that is, the aggregate movement of the rear portion of each scoop will be greater than the aggregate movement of the front portion, so that when the bucket begins to close the rear portions of the scoops swing rapidly out and down, causing the bottoms of the scoops to enter the material at an advantageous angle for penetrating the same. As the bucket continues to close the said angle of penetration is constantly reduced until the bottoms of the scoops assume a practically horizontal position. The material excavated readily passes into the back part of the respective scoops, and the final closing operation does not involve any compressing or displacing of the load in the bucket.

In the accompanying drawings, Figure I shows a side elevation of my combined bucket and operating mechanism therefor. Fig. II shows a side elevation of my improved bucket and operating mechanism therefor with the bucket open. Fig. III shows an end elevation with the bucket closed. Fig. IV shows a top plan with the bucket closed.

Referring to the drawings, *a* represents the framework for supporting the bucket and operating mechanism, which preferably comprises two approximately triangular side

plates a' and a^2 , secured together by braces or cross-bars a^3 , a^4 , a^5 , and a^6 , respectively. A shaft b is mounted centrally in the framework a , so that its ends project beyond the side plates a' and a^2 . On the shaft b within the framework are rigidly keyed two power-wheels d and e , respectively. These power-wheels have cable-grooves b' and b^2 formed in their respective faces. On the ends of the shafts b without the framework are rigidly keyed two small drums d' and e' . On each side of the shaft b is mounted a shaft f and g , respectively, so that the ends thereof project beyond the framework. On the projecting ends of the said shafts f and g are mounted segmental cam-wheels f' , f^2 , g' , and g^2 , respectively. The faces of these cam-wheels are provided with cable-grooves f^3 , f^4 , g^3 , and g^4 , respectively.

In the upper part of the framework a are mounted two parallel shafts h and l . Loosely mounted on the shaft h are three pulleys h' , h^2 , and h^3 . These pulleys are retained in their respective positions on the shaft h by means of spacers h^5 .

Near the top of the framework a , on the center line thereof, is mounted a shaft n , directly over the shaft b . To this shaft are rotatably secured four arms r , r' , s , and s' , respectively. The arms r and s and r' and s' , respectively, lie on opposite sides of the shaft b between the frame and the cable-drum. These arms extend a short distance below the bottom of the framework a , and in the free ends thereof are formed sockets r^2 , r^3 , s^2 , and s^3 , respectively.

A bucket j is suspended immediately below the framework a and comprises two scoops t and u . Each scoop is practically rectangular in cross and longitudinal section and has a flat bottom and straight cutting edge. The front end of the scoop t is suspended from the framework a by means of a shaft t' , which passes through the sockets r^2 and s^2 in the lower ends of the arms r and s , respectively. The rear end of the scoop is supported by a shaft t^2 , which passes through the outer circumference of the cam-wheels f and f' , respectively. The shaft t^2 is preferably mounted in bearings formed in the ears t^3 and t^4 , respectively, secured to the rear end of the scoop. The scoop u is suspended in a similar manner, being supported at its front end by the shaft u' , which passes through the sockets r^3 and s^3 , formed in the ends of the arms r' and s' , respectively. The rear end of the scoop is suspended from the cam-wheels g' and g^2 , respectively, by means of a shaft u^2 , mounted in bearings in the ears u^3 and u^4 .

d^3 and e^3 respectively represent the cables for operating the power-wheels to close the bucket and are secured to and adapted to wind upon the power-wheels d and e , their free ends being carried up over the pulleys h' and h^3 in the top of the frame to one of the sheaves of a hoisting-engine or similar device.

k represents a cable secured to the drum d' and the cam-wheel f' .

k' represents a cable secured to the drum d' and the cam-wheel g' .

k^2 represents a cable secured to the drum e' and the cam-wheel f^2 .

k^3 represents a cable secured to the drum e' and the cam-wheel g^2 .

k^4 and k^5 represent cables, the lower ends of which are secured to the rear ends of the respective scoops t and u , their free ends being carried up over the pulleys h^2 and l' , respectively, to another sheave of a hoisting-engine, before mentioned.

When it is desired to open the bucket, the cables d^3 and e^3 are slackened, throwing the weight of the frame upon the cables k^4 and k^5 , secured to the backs of the respective scoops. The pull on the rear end of the scoop causes them to swing apart, the rear portions traveling upwardly with their respective cam-wheels. As the cam-wheels rotate the cables are unwound from the drums d' and e' , respectively, rotating the power-wheels d and e and winding the slack cables d^3 and e^3 in the cable-grooves b' and b^2 in the respective power-wheels. To close the bucket, the cables k^4 and k^5 are slackened and a strain is put upon the cables d^3 and e^3 , causing the power-wheels d and e to rotate, winding up the cables secured to the cam-wheels f' and g' and f^2 and g^2 , respectively, upon the drums d' and e' . As the cam-wheels rotate the rear portions of the scoops are carried out and down and the front portions swing toward each other on the arms r and s and r' and s' , respectively.

What I claim is—

1. In a combined clam-shell bucket and operating mechanism therefor, a frame, a power-transmitting mechanism mounted in said frame, a scoop, a shaft mounted near the center line of said frame, a support rotatably suspended from said shaft and having its lower end secured to the front end of said scoop, a second shaft mounted below the first-mentioned shaft and at a greater distance from the center line of the frame than the first-mentioned shaft, a support rotatably suspended from said last-mentioned shaft and secured at its lower end to the rear end of said scoop, and means for operatively connecting the power-transmitting mechanism with said scoop.

2. In a combined clam-shell bucket and operating mechanism therefor, a frame, a power-transmitting mechanism mounted in said frame, two scoops located below said frame and adapted to form a single receptacle, a shaft mounted near the center line of said frame, supports suspended from said shaft and connected at their lower ends with the front ends of the respective scoops, shafts mounted near the sides of said frame below the first-mentioned shafts, supports suspended from said shafts and connected at their

lower ends with the rear ends of the respective scoops, and means for connecting the respective scoops with the power-transmitting mechanism.

5 3. In a combined clam-shell bucket and operating mechanism therefor, a frame, a power-wheel mounted in said frame, means for operating the said wheel, a cam-wheel operatively connected to said power-wheel, and a 10 scoop, one end of said scoop being secured to and rotatably supported at a point on the outer circumference of said cam-wheel, and the other end being movably supported from the said frame.

15 4. In a combined clam-shell bucket and operating mechanism therefor, a frame, a power-wheel mounted in said frame, means for operating the said wheel, cam-wheels mounted on each side of said power-wheel and operatively connected with the said power-wheel, and two scoops adapted to form a single receptacle, the rear end of each of said scoops being secured to and rotatably supported from one of the said cam-wheels, and the front end 25 of each scoop being movably supported from the said frame.

5. In a combined clam-shell bucket and operating mechanism therefor, a frame, a power-wheel mounted in said frame, means for operating the said wheel, a cam-wheel operatively connected to said power-wheel, and a scoop having one end secured to and rotatably supported at a point on the outer circumference of the said cam-wheel, and having the other end supported by arms rotatably secured in the said frame at a point above the said cam-wheel, substantially as described, and for the purpose set forth.

6. In a combined clam-shell bucket and operating mechanism therefor, a frame, a power-transmitting mechanism mounted in said frame, two cam-wheels, one of said cam-wheels being mounted at each side of said frame and operatively connected with the said 45 power-transmitting mechanism, a scoop located below each cam-wheel and having its rear end suspended from a point on the outer circumference of the adjacent cam-wheel, and its front end supported by arms rotatably secured in the said frame at a point above the 50 said cam-wheel, substantially as described and for the purpose set forth.

7. In a combined clam-shell bucket and operating mechanism therefor, a frame, two scoops supported below said frame and adapted to form a single receptacle, the front end of each of the said scoops being supported by arms rotatably supported from a common shaft in said framework, the rear end of each scoop being supported from a shaft located in the said framework below the first-mentioned shaft, and not in the same vertical plane therewith, a power-wheel mounted in said framework, and means for operatively connecting the said scoops and the said power-wheel.

8. In a combined clam-shell bucket and operating mechanism therefor, a frame, a shaft rotatably mounted in said frame, a power-wheel rigidly mounted on said shaft, a hoisting-cable secured to said power-wheel, a cable-drum rigidly mounted on the outer end of said shaft, a cam-wheel rotatably mounted in said frame, a cable operatively connecting said cable-drum and said cam-wheel, a shaft mounted in said frame above the said power-wheel, a support rotatably suspended from said shaft, and a scoop secured at its rear end to said cam-wheel and at its front end to the said support, substantially as described, and for the purpose set forth.

9. In a combined clam-shell bucket and operating mechanism therefor, a frame, a power-wheel shaft rotatably mounted in said framework, a power-wheel rigidly mounted on said shaft, a hoisting-cable operatively secured to said power-wheel, a cable-drum rigidly mounted on said power-wheel shaft, cam-wheels rotatably mounted in said framework on each side of said power-wheel shaft, cables connecting the said cable-drum and said cam-wheels, supports rotatably secured in said framework above the said power-wheel shaft on each side thereof and extending down below the bottom of the said framework, and a scoop operatively secured to the respective cam-wheels and the respective supports on each side of the said power-wheel shaft.

Signed by me at Cleveland, Ohio, this 9th day of March, 1901.

FRANK E. HULETT.
